(57) **CLAIM**

The ornamental design for a graphical user interface for a display screen or a portion thereof, as shown and described.

DESCRIPTION

FIG. 1 is a front view of a graphic user interface for a display screen or portion thereof showing our new design; and,

FIG. 2 is a front view of a second embodiment thereof.

The broken line showing of the display screen or portion thereof in the figures is not part of the claimed design.

1 Claim, 2 Drawing Sheets

FIG. 1

FIG. 2
